UNITED STATES PATENT OFFICE.

CHETWOOD SMITH, OF WORCESTER, MASSACHUSETTS.

ALARM CONTROL FOR SPRINKLER SYSTEMS.

1,134,645.

Specification of Letters Patent.

Patented Apr. 6, 1915.

Application filed December 19, 1914. Serial No. 878,182.

To all whom it may concern:

Be it known that I, CHETWOOD SMITH, a citizen of the United States, residing at Worcester, in the county of Worcester and

5 State of Massachusetts, have invented a new and useful Alarm Control for Sprinkler Systems, of which the following is a specification.

This invention relates to an alarm control 10 for sprinkler systems and particularly to means for increasing the reliability in operation of the alarm under certain unusual or extreme conditions.

The invention is designed for use in connection with sprinkler systems in which the 15 alarm is connected to the supply pipe of the sprinkler system at a point adjacent the check valve in said supply pipe. It is necessary that the alarm should operate whenever 20 one or more sprinklers open and cause a flow of water through the supply pipe. It is customary to arrange the opening into the alarm pipe in the seat of the check valve so that the raising of the valve will admit 25 water to the alarm pipe and the closing of the valve will close the pipe. This simple arrangement is open to at least two serious objections. In the first place, water hammer in the supply pipe will often momentarily 30 raise the check valve, causing an intermittent actuation of the alarm although no sprinkler is opened. In the second place the valve in the supply pipe is necessarily of such area that the flow through a single 35 sprinkler is often insufficient to keep the valve continuously open. This likewise causes an intermittent and irregular actuation of the alarm hardly distinguishable from that produced by water hammer.

40 It is the object of my invention to provide an improved construction of alarm control by the use of which such irregular actuation of the alarm will be avoided.

With this object in view, one feature of 45 my invention consists in the provision of an auxiliary device associated with the alarm control which will be effective to prevent actuation of the alarm when the valve is opened as the result of water hammer in the 50 supply pipe.

A further feature of my invention consists in the provision of a construction by which continuous actuation of the alarm will be insured whenever one or more sprinkler 55 heads are open.

My invention further consists in certain

devices, arrangements and combinations of parts which will be hereinafter described and more particularly pointed out in the appended claims.

60 Two forms of my invention are shown in the drawings in which—

Figure 1 is a partial sectional elevation showing one form of my invention and its relation to a sprinkler system; Fig. 2 is an 65 enlarged sectional detail of a portion of the device shown in Fig. 1, and Fig. 3 is an elevation partly in section of a second form of my invention.

Referring to the drawings, 10 indicates 70 the supply pipe of a sprinkler system having any desired number of branch or service pipes 11 connected thereto, and provided with sprinklers 12. A check valve 13 is mounted in the supply pipe 10 and normally 75 rests upon the valve seat 14, as shown in Fig. 1. The seat 14 may be grooved as shown at 15 and has an opening 16 therein communicating with an alarm pipe 17.

A suitable alarm device 18 of any desired 80 form is connected for actuation by the flow of water through the pipe 17. In order that the alarm 18 may not be actuated when the check valve 13 is opened by water hammer, I provide the intermediate control devices 85 shown in Figs. 1 and 3. In the form shown in Fig. 1 this device comprises a casing 20 into which two sections 17^a and 17^b of the pipe 17 extend and within which said sections are provided with downwardly ex- 90 tending ends 21. The ends 21 of the sections 17^a and 17^b are open at their lower extremities and are positioned closely adjacent to a diaphragm 22, suitably supported upon the casing 20. A rod 23 is secured to the 95 diaphragm 22 near its center and extends upwardly through a partition 24 within the casing, the upper end of the rod being secured to a second diaphragm 25. A coil 100 spring 26 may be inserted between the dia- phragm 22 and the partition 24. This spring normally forces the diaphragm down- wardly and permits a flow of water through the casing from the section 17^a of the pipe 17 to the section 17^b. The portion of the 105 casing 20 below the diaphragm 22 is connected by a pipe 27 to the supply pipe 10 at a point below the check valve 13 while that portion of the casing 20 above the dia- phragm 25 is similarly connected by a pipe 110 28 to the supply pipe 10 at a point above the check valve 13. Suitable provision is made

to prevent leakage around the pipe sections 17^a and 17^b and the rod 23 where they pass through the partition 24 and a vent or opening 29 may be provided in the intermediate portion of the casing to prevent an accumulation of water under pressure by leakage through the openings in the partition 24. The operation of this intermediate control device will now be described. Under normal conditions the pressure in the supply pipe 10 above the check valve is equal to or greater than the pressure below the valve. As the diaphragms 22 and 25 are of equal area, an excess of pressure above the valve will force the diaphragm 22 downwardly away from the depending ends 21 of the pipe sections 17^a and 17^b, thus permitting the flow of water through the pipe 17 to the alarm 18 whenever the check valve 13 be raised as a result of the opening of one or more of the sprinkler heads. Even if the pressure above is exactly equal to the pressure below, the diaphragm will be moved downward by the spring 26. This condition obtains whenever one or more sprinkler heads 12 are opened, the resulting flow of water through the pipe 10 raising the check valve 13 or the secondary check valve 30 (hereinafter described) and permitting water to flow through the pipe 17 to operate the alarm 18. As the parts of the supply pipes above and below the valve 13 are in free communication, the pressure in the two parts must be substantially the same and the diaphragm is moved to its lower limit by the spring 26.

As previously stated the valve 13 may be opened as a result of water hammer in the supply pipe 10. In this event the pressure below the valve 13 will exceed the pressure above the valve and this excessive pressure will be communicated through the pipe 27 to the diaphragm 22 forcing the diaphragm upwardly to close the ends 21 of the pipe sections 17^a and 17^b. This action will take place substantially simultaneously with the opening of the check valve and accordingly no flow will take place through the alarm pipe. The opening of the valve by intermittent excessive pressure below the valve is therefore ineffective to ring the alarm.

It has been pointed out that the opening of a single sprinkler often induces a flow insufficient to hold the valve 13 continuously open, the actuation of the alarm becoming irregular and intermittent. To correct this irregularity I provide the construction shown on an enlarged scale in Fig. 2. This construction comprises a relatively small check valve 30 mounted upon the larger check valve 13 and covering a comparatively small opening 31 in the large valve. The weights of the two valves are so proportioned that the valve 30 will open more easily than the valve 13. A stop 32 is

mounted adjacent the valve 30 and this stop may be adjusted to limit the upward movement of the valve 30. By suitable adjustment the extreme open position of the valve may be so fixed that the flow through a single sprinkler will suffice to hold the valve open. A passage 33 is formed in the check valve 13, communicating at one end with the opening 31 which constitutes the seat of the valve 30 and at the other end with the groove 15 or the opening 16 into which the pipe 17 is connected. When thus constructed, the normal opening of either of the check valves 13 or 30 will cause a continuous flow of water through the pipe 17 to actuate the alarm 18.

In Fig. 3 I have shown a modified arrangement for controlling the flow through the pipe 17. In this form the two sections of the pipe 17, indicated in Fig. 3 as 17^c and 17^d, are connected to a sleeve or casting 40 into which are also connected the pipes 27 and 28. A piston 41 is mounted to slide freely with its opposite ends engaging the end portions of the pipes 27 and 28. The piston 41 is shown in its normal position in Fig. 3 and has a reduced central portion 42 which permits flow through the pipes 17^c and 17^d when the piston 41 is in this position. An increase in pressure in the pipe 27 will slide the piston upwardly until the lower full-sized portion of the piston closes the opening in the sleeve 40 and shuts off the flow from the pipe 17^c to the pipe 17^d. A stop pin 43 determines the normal position of the piston and a light coil spring 44 extends into a recess in the upper end of the piston and tends to return the piston to its normal position when displaced therefrom. The general operation of the device will be seen to be precisely similar to that of the form previously described.

Having thus described my invention it will be seen that other changes and modifications can be made therein by those skilled in the art without departing from the spirit and scope thereof as set forth in the claims and I do not wish to be otherwise limited to the details herein disclosed but

What I do claim is:—

1. In a sprinkler system, a supply pipe, a check valve in said supply pipe, an alarm pipe connected to said supply pipe and normally closed by said check valve, and a pressure-controlled auxiliary device connected to said supply pipe on both sides of said check valve, said device being effective to close said alarm pipe whenever the pressure of the supply pipe below the check valve exceeds the pressure in said pipe above the check valve.

2. In a sprinkler system, a supply pipe, a check valve in said pipe, an alarm pipe connected to said supply pipe and normally closed by said check valve, and an

- auxiliary device in said alarm pipe connected to said supply pipe on each side of the check valve, said auxiliary device being effective to close the alarm pipe whenever excessive pressure occurs below the check valve.
3. In a sprinkler system, a supply pipe, a check valve in said pipe, an alarm pipe normally closed by said check valve, and a cut-off device operative upon said alarm pipe, said cut-off device being controlled by the difference in relative pressure in said supply pipe, above and below said check valve.
4. In a sprinkler system a supply pipe, a check valve in said pipe, an alarm pipe normally closed by said check valve and having a control portion intermediate its ends, and controlling means connected to said supply pipe on each side of said check valve, each means comprising a movable member effective to prevent flow through the control portion and the alarm pipe whenever excessive pressure occurs below the check valve.
5. In a sprinkler system, a supply pipe, a check valve in said supply pipe, an alarm pipe connected to said supply pipe and normally closed by said check valve, a valve in said alarm pipe positioned intermediate its ends, and devices for opening and closing said valve, said devices being effective to close said valve whenever the pressure in the supply pipe below the check valve exceeds the pressure above the check valve and being effective to open said valve under all other pressure relations.
6. In a sprinkler system, a supply pipe, a check valve in said supply pipe connected to said supply pipe and normally closed by said check valve, a piston valve slidable transversely of said alarm pipe, and pressure connections from opposite ends of said piston valve to said supply pipe at points above and below said check valve, said piston valve being movable under variations in relative pressure in said supply pipe to open or close said alarm pipe.
7. In a sprinkler system, a supply pipe, a check valve in said supply pipe, an alarm pipe connected to said supply pipe and normally closed by said check valve, and a relatively small check valve mounted on said first named check valve, the larger check valve having a passage therein communicating at one end with the alarm pipe and having its opposite end normally closed by the smaller check valve.
8. In a sprinkler system, a supply pipe, a check valve in said supply pipe, an alarm pipe connected to said supply pipe and normally closed by said check valve, a relatively small check valve mounted on said first named check valve and connections from said small check valve to the alarm pipe, whereby the opening of either valve will permit a flow of water through the alarm pipe.

In testimony whereof I have hereunto set my hand in the presence of two subscribing witnesses.

CHETWOOD SMITH.
